Application August 3, 1955, Serial No. 526,284

8 Claims. (Cl. 41—9)

This invention relates to etching machines for etching printing plates and the like and has specific reference to a machine wherein etching acid is continuously sprayed against the plate during the etching process and where an irregular motion is imparted to the plate during this process to insure that the etching will be uniform throughout the entire area of the plate.

Objects and advantages of the invention will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

In the drawings:

Figure 1 is a plan view of the etching machine of the present invention with portions of the machine being broken away and with the mechanism for imparting an irregular motion to the printing plate shown mounted on top of the machine.

Figure 2 is a front elevational view of this mechanism for imparting an irregular motion to the printing plate and is taken generally from line 2—2 of Figure 1.

Figure 3 is a rear view of the carriage which forms a part of this mechanism with this view being taken from line 3—3 of Figure 1 and showing in detail the sector gear drive for imparting a reciprocating motion to the carriage.

Figure 4 is an end view of the mechanism for imparting an irregular motion to the printing plate and is taken generally from line 4—4 of Figure 2.

Figure 5 is a sectional view of this mechanism taken along line 5—5 of Figure 2.

In etching machines of the type to which the present invention pertains, etching acid is contained in a housing or tank and is continuously sprayed by suitable mechanism against a printing plate introduced and retained in the housing for the time necessary to etch the plate as desired. In order to have uniform acid distribution and accordingly uniform etching of the printing plate it has been recognized that it is highly desirable to continuously move the plate through a constantly varied motion pattern during the etching process with the motion that is imparted to the plate preferably being both reciprocatory and rotary and restricted to a plane generally normal to the direction of spray projection. While there are several known etching machines which provide an irregular motion pattern for the plate being etched during the etching process, such as the machines disclosed in United States Patent Numbers 2,669,048 and 2,700,838 issued to J. A. Easley et al. and W. E. Guenst, respectively, each of these known machines have certain inherent undesirable characteristics in that an irregular motion pattern of the plate is not insured or operational difficulties are experi-

enced because of the particular design and construction of the drive mechanism with stoppages, breakdowns, and/or repairs being relatively frequent.

The present invention has for its object the provision of an improved etching machine of the type wherein during the etching process acid is continuously sprayed against the plate while the latter is moved in an irregular motion pattern. Another object of the invention is to provide such an etching machine wherein the drive for imparting this irregular motion to the plate includes a rack and pinion with the rack being in the form of a worm that is continuously rotated during the etching process and with the pinion being in the form of a worm wheel intermeshed with the worm. Another object of the invention is to provide such an etching machine having this drive and wherein the plate to be etched is supported from a carriage that is continuously reciprocated through a predetermined amplitude with the worm wheel being mounted on and carried by the carriage and with the worm being mounted on the machine free of the carriage. Another object of the invention is to provide such an etching machine wherein the worm and the carriage are driven through a common drive mechanism. Another object of the invention is to provide such an etching machine wherein this mechanism for imparting an irregular motion to the plate is mounted for simultaneous movement to and from a position where the plate is operatively disposed within the machine and a position where the plate is located exteriorly of the machine, with this movement being permitted only when the plate is within a limited range of rotative positions and with an indicator being provided to indicate the rotative position of the plate. A further object of the invention is the provision of such an etching machine that is rugged and highly reliable in its operation and which results in uniform etching of the plate.

In accordance with the present invention the etching machine comprises a housing or tank upon the top or side of which is mounted mechanism effective to impart an irregular motion to a printing plate that is supported within the housing and has acid sprayed against its face by any suitable means. The plate is removably secured to a support member disposed on the end of a shaft that extends outwardly through a slot provided in the top or wall of the housing and which is carried by a carriage in a manner permitting rotation of the shaft about its axis. The carriage is mounted on the etching machine in a manner so that it may be reciprocated longitudinally of this slot with the carriage and accordingly the shaft connected thereto being continuously reciprocated at a uniform linear velocity through a motor driven drive including a sector or mangle gear rotated by a motor through a speed reducer and positioned between a pair of toothed racks provided on the carriage for alternate engagement with these racks. The shaft is rotatably driven in response to reciprocation of the carriage by a drive assembly that includes a pair of intermeshed gears one of which is secured to the shaft while the other is secured to a drive shaft that is journaled to the carriage in parallel spaced relation with the shaft that carries the plate to be etched. Also secured to this drive shaft is a pinion which is continuously intermeshed with a rack which is mounted upon the machine free of the carriage and extends in parallel relation with the axis of reciprocation of the carriage. This pinion is in the form of a worm wheel while the rack is in the form of a worm and is mounted upon the etching machine in a manner so that it may rotate about its axis but is prevented from moving in a longitudinal or axial direction. During reciprocation of the carriage the worm is continuously rotated and for this purpose suitable drive mechanism is provided with this drive mechanism being driven by the same motor that drives

the sector or mangle gear through which the carriage is continuously reciprocated and with the rotation imparted to the worm being such as to continuously vary the rotative position of the plate relative to its linear position with successive reciprocations of the carriage and accordingly imparting an irregular motion pattern to the plate. This mechanism for imparting this irregular motion to the plate is mounted upon a portion of the machine which provides for pivotal movement of this mechanism to and from an operative position where the plate is operatively disposed within the machine and a position where the plate is located exteriorly of the machine and may readily be attached or removed from this mechanism. The opening provided in the cover or wall of the machine and through which the plate must pass during this pivotal movement is generally of such size that the plate must be in a particular position in order to be able to pass through this opening. For this reason an indicator is provided for indicating the rotative position of the plate when it is in its operative position within the machine with the indicator being visible exteriorly of the machine and being actuated through the shaft upon which the plate is supported.

It will be understood that the foregoing general description and the following detailed description as well are exemplary and explanatory of the invention but are not restrictive thereof.

Referring now to the drawings, wherein like reference characters are used throughout to designate like elements, the illustrative and preferred embodiment of the invention disclosed therein comprises a housing or tank 10, only a fragmentary portion of which is shown, and which is adapted to contain a suitable etching fluid as well as suitable means for continuously spraying the fluid against the face of a printing plate that is to be etched, all as is well known in the art.

Mounted upon housing 10 is the mechanism 12 which supports printing plate 14 within the housing and imparts an irregular motion to the plate during the etching operation. While this mechanism is shown as mounted on the top or cover of the housing it may equally well be mounted upon a vertical or slanted wall of the housing so long as the acid spray impinges against the face of plate 14. The mechanism 12 comprises a frame member 20 overlying and secured to the top of housing 10. Mounted immediately above and in spaced relation to this frame member is the carriage 21 which is received or supported upon the parallel, laterally spaced support rods 22 and 24 for reciprocal movement therealong with these rods being secured to and extending between spaced support brackets 26 and 28 which extend upwardly from frame member 20. The carriage 21 comprises the generally horizontally disposed body member 30 to one end of which is secured, by cap screws 32, the upright plate member 34 and on the other end of which is mounted spaced rollers 38 which embrace rod 24 therebetween. Extending inwardly from the inner face of plate 34 are the spaced ears 40 which are provided with coaxial bores within which support rod 22 is snugly but slidably received.

Reciprocation of carriage 21 along the spaced parallel rods 22 and 24 is effected through a suitable motor driven drive mechanism which includes motor 42 and speed reducer 44 both of which are mounted upon support frame 20 and are operatively interconnected. Extending from and forming a part of speed reducer 44 is shaft 46 upon the end of which is secured sector or mangle gear 48 which is driven at a uniform speed by motor 42 through speed reducer 44. This sector gear 48 is interposed between the spaced toothed racks 50 and 52, which are secured to the inner surface of spaced flanges 54 and 56, respectively, that extend laterally from plate member 34 with these racks being retained in position by screws 58 that extend through the respective flanges. These racks are in parallel relation with support rods 22 and 24 and are alternately engaged by the toothed portion of the sec-

tor gear as it is rotated by motor 42 to thereby effect reciprocation of the carriage. Through this sector gear drive carriage 21 may be continuously reciprocated with the amplitude of the reciprocation in each direction being equal to the circumferential length of the arc of the toothed portion of this gear and with the linear velocity of the reciprocation being uniform throughout each reciprocal movement. Reciprocal movement of the carriage is limited by spaced stops 60 secured to rod 22 with these stops being so positioned that gear 48 will properly mesh with the teeth of racks 50 and 52 upon becoming disengaged from one and engaged with the other of these racks.

Carried by and journaled to body member 30 of carriage 21 are the spaced parallel shafts 60 and 62 each of which extends through this body portion with shaft 62 being mounted within spaced bearings 64 secured within bore 66 and with shaft 60 being mounted within spaced bearings 68 secured within bore 70. Axial movement of each of these shafts is prevented by collars 72 which are secured to the shafts at a location immediately outwardly of each of the bearing members. Frame member 20 and housing 10 are provided with an elongated slot 74 parallel with the axis of reciprocation of the carriage and through which extends shaft 60 with flange 76 being secured to the inner end of this shaft. The printing plate 14 is supported within housing 10 during the etching process by support plate 78 which is secured to the inner surface of flange 76 by screws 80 with special clamp means 81 being provided to permit easy attachment and removal of the printing plate to and from the support plate and with these clamps being adjustable to accommodate plates of different sizes. Leakage of acid spray from the interior of housing 10 along shaft 60 is prevented by baffle plate or ring member 82 which is positioned immediately below housing 84 secured to the underside of the top wall of tank 10 and within which housing is disposed floating ring 85 with this baffle plate, housing and ring forming a labyrinth which effectively prevents the escape of acid spray from within the tank or housing 10.

Rotation of shaft 60 is effected in response to reciprocation of the carriage through the drive assembly designated on the drawings generally as 84 and which includes rack member 86 in continuous engagement with which is pinion 88 mounted upon and secured to the upper end of shaft 62. Also secured to shaft 62 is gear 90 which is intermeshed with gear 92 disposed upon and secured to shaft 60 so that the rotation of shaft 62 is imparted to shaft 60 through these gears 90 and 92. Rack member 86 extends between and is journaled to spaced support brackets 26 and 28 so that the rack is free to rotate about its axis but is prevented from movement in an axial direction. As carriage 21 is reciprocated in opposite directions along rods 22 and 24 shaft 60 is rotated in opposite directions through this rack and pinion drive with pinion 88 being continuously intermeshed with rack 86 and caused to rotate by axial movement of the carriage.

As embodied, rack and pinion 86 and 88 are in the form of a worm and worm wheel, respectively, and in order to provide an irregular motion pattern for plate 14 this worm 86 is continuously rotated during reciprocal movement of the carriage at such a speed that the rotative position of the plate relative to its linear position is varied with each reciprocation of the carriage.

Rotation of rack or worm 86 is had through a suitable drive mechanism which, like sector gear 48, is driven by motor 42 through speed reducer 44 with this drive mechanism including shaft 94 which extends through and is journaled within housing 96 which forms a part of support bracket 28. Secured to one end of the shaft is pulley 98 which is interconnected with and driven from pulley 100 by belt 102 with this later pulley being mounted upon shaft 46. On the other end of shaft 94

is secured worm 104 which is continuously intermeshed with worm wheel 106 secured to the end of rack or worm 86. Thus, as carriage 21 is reciprocated through motor 42, speed reducer 44, and sector gear 48, worm 86 is continuously rotated at a relatively slow speed so that an irregular motion pattern for plate 14 is established.

In order to facilitate attachment and removal of plate 14 to and from support plate 78 the mechanism 12 is preferably mounted upon a portion of housing 10 which is hinged so that this mechanism may be pivoted from its operative position depicted in the drawings to a position where the plate is located exteriorly of the housing and accordingly is readily accessible. In the illustrative organization the portion 108 of the cover of the machine may be pivoted in this manner through the medium of hinges 110 with the plate 14 passing out through opening 109 provided in the top of the machine as this portion 108 is pivoted upwardly and with gasket 111 providing a fluid tight seal when this portion 108 is in its lowermost position and plate 14 is operatively disposed within the machine. Alternatively, rather than hinging only a portion of the cover of the machine the entire cover may be pivotally mounted if desired.

With certain sizes of printing plates that are utilized it is necessary that the plate be in a particular rotative position or in other words have a particular orientation with respect to the housing or tank 10 before mechanism 12 may be pivoted either to or from its operative position, where the plate is located within housing 10, since otherwise the plate would contact the wall of the housing and prohibit this pivotal movement. Inasmuch as it is impossible to determine the exact rotative position or orientation of plate 14 after the etching operation is complete without gaining access to the interior of housing 10, a suitable indicator is provided which is visible exteriorly of the machine and provides a continuous indication of the rotative position of the plate with this indicator comprising dial 112 formed on the end of support member 114 which is provided with laterally extending bosses 116 and is supported from body member 30 of carriage 21 by means of spaced arms 118 which are secured to these respective members by cap screws 120. Extending through and journaled within the bore provided in support member 114 is shaft 122 to one end of which is secured beveled gear 124 that is intermeshed with an identical gear 126 secured to the upper end of shaft 60. On the other end of shaft 122 is secured pointer 128 which overlies the face of dial 112 with suitable indicia 130 being provided on this dial so that when pointer 128 is positioned therebetween the rotative position of plate 14 within housing 10 is such as to permit pivotal movement of mechanism 12 about hinges 110 to a position where the plate is located exteriorly of housing 10 thereby permitting the plate to be readily removed and another readily attached to the support plate 78.

In operating the present invention a printing plate that is to be etched is attached to support plate 78 by means of the clamps 81 and the cover or the portion of the cover 108 together with mechanism 12 is then moved to its operative position where plate 14 is disposed within housing 10. During the etching process this printing plate is continuously reciprocated through a predetermined amplitude through the toothed arc of sector gear 48 and the spaced toothed racks 50 and 52 with this drive mechanism being effective to move the carriage 21 and the plate at a constant linear velocity throughout the extent of their movement in each direction and with acid being continuously sprayed or splashed against the inner surface of the plate during this reciprocal movement.

In response to reciprocation of the carriage through its opposite directions of movement shaft 60 and accordingly plate 14 are rotated in opposite directions through

the rack and pinion drive 86 and 88. Rack or worm 86 is continuously rotated during reciprocal movement of the carriage with the rotation of this worm being at a relatively slow speed such as to provide an irregular motion pattern for the plate with the respective linear and rotative positions of the plate varying with each reciprocal movement.

Thus, with the present invention not only is the motion pattern of the plate irregular during the etching process, but the linear and rotative velocities imparted to the plate are uniform and do not vary widely, as was the case heretofore, resulting in more uniform distribution of the acid over the total area of the plate and accordingly more uniform etching.

15 The invention in its broader aspects is not limited to the specific mechanism shown and described but departures may be made therefrom, within the scope of the accompanying claims, without departing from the principles of the invention and without sacrificing its chief advantages.

What is claimed is:

1. In an etching machine of the type wherein acid is continuously sprayed against a plate to be etched, the combination of a carriage mounted for reciprocation through a fixed amplitude, means for reciprocating said carriage including a pair of parallel spaced toothed racks mounted on the carriage, a motor driven sector gear between the racks alternately engaging one or the other of said pair of racks, a rotatable plate support mounted on said carriage, a pinion driving said support, a rack mounted parallel to the path of carriage reciprocation and in driving engagement with said pinion, means driven from said motor for continuously progressing said rack during reciprocation of the carriage, support and pinion whereby relative rotational position of said support with respect to its linear position varies with each reciprocation of the carriage.

2. In an etching machine of the type wherein acid is continuously sprayed against the plate to be etched, the combination of a carriage mounted on said machine for reciprocation through a fixed amplitude, means for continuously reciprocating said carriage, a support rotatably mounted on said carriage for movement therewith to support a plate to be etched, means for rotating said support in response to reciprocation of said carriage including a worm and a worm wheel continuously intermeshed therewith, said worm wheel being rotatably carried by said carriage and effectively interconnected with said support, said worm being rotatably mounted on the machine in generally parallel relation with the axis of reciprocation of the carriage and held against axial movement thereof relative to the machine, said worm being continuously rotated about its axis during reciprocation of carriage.

3. The etching machine of claim 2 wherein the means for reciprocating the carriage through a fixed amplitude comprises a pair of spaced toothed racks mounted on said carriage in parallel relation with the axis of reciprocation of the carriage and a motor driven sector gear stationarily mounted on said machine for rotation about its axis and interposed between said racks for alternate engagement therewith.

4. In combination with an etching machine of the type described, a carriage mounted thereon for reciprocating movement, means for continuously reciprocating said carriage through a fixed amplitude, a shaft carried by and journaled to said carriage, said shaft extending into said machine and carrying on its inner end a support for a plate to be etched, a rack in the form of an elongated worm mounted on said machine in parallel relation with the axis of reciprocation of said carriage and in a manner permitting rotation about its axis but preventing axial movement thereof relative to said machine, said worm being continuously rotated during reciprocation of the

7
carriage, a worm wheel intermeshed with said worm and carried by said carriage, said worm wheel being rotatable about its axis and being effective to rotate said shaft.

5. The etching machine of claim 4 wherein rotation of the worm and reciprocating carriage are driven by a common motor.

6. The organization of claim 5 wherein the drive for rotating the worm during reciprocation of the carriage includes a reduction gear train with a driven gear secured to one end of said worm and having a driving gear 10 intermeshed therewith.

15 7. An etching machine of the type wherein during the etching process acid is continuously sprayed against the face of the plate to be etched while an irregular motion is imparted to said plate comprising in combination, a container within which the acid is contained and the plate disposed during the etching process, mechanism mounted on a wall of the container to support said plate and impart an irregular motion thereto, said mechanism including a carriage mounted for reciprocation through a predetermined amplitude, means for continuously reciprocating said carriage including a motor and drive mechanism, a shaft carried by and journaled to said carriage, said shaft extending into said machine and carrying on its inner end a support for a plate to be etched, a drive shaft 20 carried by and journaled to said carriage in spaced relation to said shaft carrying said support and being interconnected therewith through a gear train, a worm wheel mounted on and secured to said drive shaft, a rack in the form of an elongated rotatable worm mounted on 30 said machine in parallel relation with the axis of recip-

rocation of said carriage and held against axial movement relative to said machine, said worm and worm wheel being continuously intermeshed, and means for continuously rotating said worm during reciprocation of the carriage and including a worm wheel secured to said shaft and intermeshed with a worm journaled to the machine and driven by said motor.

8. In an etching machine of the type wherein acid is continuously sprayed against a plate to be etched, the combination of a carriage mounted for reciprocation through a fixed amplitude, means for reciprocating said carriage including a drive motor, a rotatable plate support mounted on said carriage, a pinion driving said support, a rotatable rack mounted parallel to the path of carriage reciprocation and in driving engagement with said pinion and means driven through reduction gearing from said motor for continuously rotating said rack during reciprocation of the carriage, support and pinion whereby relative rotational position of said support with respect to its linear position varies with each reciprocation of the carriage.
